UNITED STATES PATENT OFFICE.

HENRY J. JARRY, OF FALL RIVER, MASSACHUSETTS, ASSIGNOR OF ONE-HALF TO JAMES A. McLANE, OF FALL RIVER, MASSACHUSETTS.

PICKER-STICK CHECK.

SPECIFICATION forming part of Letters Patent No. 752,342, dated February 16, 1904.

Application filed October 24, 1903. Serial No. 178,430. (No model.)

To all whom it may concern:

Be it known that I, HENRY J. JARRY, a citizen of the United States, residing at Fall River, in the county of Bristol and State of Massachusetts, have invented new and useful Improvements in Picker-Stick Checks, of which the following is a specification.

My invention relates to picker-stick checks for looms, the purpose of which is to check and hold the picker-stick and prevent the tendency of the shuttle to rebound and knock off the filling or weft, and has for its object to provide a device of this character which will be simple of construction, durable in use, comparatively inexpensive of production, and which can be easily attached to looms now in general use.

More particularly, one of the objects of my invention is to provide a device of this nature which will be readily capable of adjustment so that it will offer more or less resistance to the picker-stick or, to use the technical terms of the art, which can be adjusted so that it will be "short and sharp" or "long and easy."

With this and other objects in view the invention consists of certain novel features of construction, combination, and arrangement of parts, which will be hereinafter more fully described, and particularly pointed out in the claims.

In the accompanying drawings, Figure 1 is a side elevation illustrating my improved check applied to the picker-stick of a loom. Fig. 2 is a bottom plan view thereof, the picker-stick being shown in section. Fig. 3 is a section through the blade of the check and the adjustable stop on the line 3-3 of Fig. 1, the spring being omitted. Fig. 4 is a section through the pivotal axis of the blade on the line 4-4 of Fig. 1.

Referring to the drawings, 1 represents the lay-beam, and 2 the slot therein, in which the picker-stick 3 works.

4 is a leather buffer against which the picker-stick strikes on its return after having delivered the shuttle.

5 is a plate secured to the under face of the beam 1 by screws 6 and having an offset por-

tion 7, to which the blade 8 of the check is pivoted by the means now to be described. 50

Through a slot 9, formed in said offset portion 7 of the plate 5, (see Fig. 4,) is passed a bolt 10, having a nut 11 on its outer end. Sleeved on this bolt is a bushing 12, having a reduced portion 13, on which the blade 8 is 55 rotatably mounted. The opposite end 14 of the bushing 12 is octagonal or angular in shape, so that it may be held from turning when the nut 11 is tightened up. Adjacent to said angular portion 14 the bushing is provided with 60 a flange portion 15 on one side and a larger flange portion 16 on the opposite side. Between these flange portions and the blade 8 are arranged several coils of a torsion-spring 17, one end of which is bent down and under to 65 engage one of the recesses 18, formed in the end shoulders 19 of the flange portion 16, as shown in Figs. 1, 2, and 4. The other end of the spring 17 extends back of the blade 8 to a point slightly beyond the longitudinal center 70 thereof, where it presses against the back of said blade. This end of the spring 17 is also arranged to approximately bear in the middle of the vertical width of said blade, as clearly shown in Fig. 1. 75

By providing the two shoulders 19, having the recesses 18, the picker-check is rendered capable of being placed on the other side of the slot 2 of the lay-beam 1 by using a spring, blade, and plate 5 of opposite hand, in which case the bent end of the spring 17 would engage the other shoulder 19 from that shown in the drawings. In other words, the check is capable of use either on the right or on the left side of the picker-stick or on either end 85 of the lay-beam. In this connection it may also be said that the means of attaching my improved picker-stick check will necessarily vary according to the type of loom in which it is employed, so that I do not in any way 90 restrict myself to the specific attaching means which I have chosen to illustrate and describe herein, said means serving as an example of the means which may be employed. By loosening the nut 11 of the bolt 10 and turning 95 the bushing 12 relatively to said bolt by means

of a wrench applied to the angular portion 14 of said bushing the pressure exacted by the spring 17 on the blade 8 of the check may be increased or decreased, as will be obvious 5 upon reference to Fig. 2 of the drawings.

The slot 9 in the offset portion 7 of the plate 5 permits of the adjustment of the bolt 10 and the parts carried thereby toward or away from the picker-stick slot 2, which adjustment aids in regulating the resistance offered by the check to the picker-stick, as will be more fully described later.

In order to further regulate the angle at which the blade 8 normally stands in the path 15 of the stick, and consequently to aid, in connection with the adjustment just described, the resistance of the blade to the stick, the following means are provided.

Integrally formed with the blade 8 and projecting therefrom rearwardly at approximately 20 the longitudinal center of said blade is a bracket 20, carrying at its free end an upwardly-projecting lug 21. Coöperating with said lug to stop the movement of the blade 8 toward the slot 2 is a lug 22, forming part of 25 a block 23, which is slidably held to the plate 5, adjacent to one end of the offset portion 7 thereof, by the screw 24, said screw passing through a slot 25 (shown in dotted lines 30 in Figs. 2 and 3) in the plate 5, whereby the block 23 and lug 22 can be adjusted toward or away from the picker-stick slot 2.

The front side of the blade 8, or that which engages the picker-stick, is slightly concaved, 35 as shown in Fig. 2, whereby the resistance to the picker-stick is made to progressively increase, which result is also obtained by the progressive compression of the spring 17 as the blade 8 is forced backwardly by said stick.

It will now be seen that by means of the 40 adjustment provided at the pivotal axis of the blade of the check and of the adjustment of the stop-block 23 not only can the angle at which the blade normally stands with reference to the slot 2 be varied at will, but also 45 that the blade can be bodily adjusted laterally with respect to said slot without changing the angle that it makes therewith. These features, taken in connection with the adjustment 50 ability of the force with which the spring 17 presses upon the blade, enable the resistance offered by the check to the picker-stick to be varied within wide limits, so that it may be set as "short and sharp," or "long and easy," 55 or with any intermediate degree of resisting capacity.

Having thus described one form in which my invention may be embodied, and without restricting myself to the precise forms and dimensions shown, what I claim is—

1. A picker-stick check for looms, comprising a check-blade pivotally supported adjacent to the picker-stick slot in the lay-beam, means to adjust the pivot of said blade toward and

away from said slot, a spring arranged to 65 normally hold said blade projecting over said slot, a stop to limit the movement of said blade under the influence of said spring and means to adjust said stop toward and away from said slot.

2. A picker-stick check for looms, comprising a check-blade pivotally supported adjacent to the picker-stick slot in the lay-beam, a spring attached to the pivot of said blade and extending back thereof, a stop on the back of 75 said blade and a coöperating stop on the lay-beam, said pivot and said coöperating stop being both adjustable toward and from the slot in the lay-beam.

3. A picker-stick check for looms comprising 80 a plate adapted to be mounted on the lay-beam at one side of the slot therein, a check-blade pivotally supported on said plate, the pivot of said blade being adjustable transversely of said plate so as to bring it nearer 85 to or farther from said slot when the plate is in position on the lay-beam, a spring attached to said pivot and arranged to press said blade outwardly in a direction to project over said slot, when said plate is in position on the lay-beam, and a stop to limit the outward movement of said blade, said stop also being adjustable transversely of said plate.

4. A picker-stick check for looms, comprising 90 a plate adapted to be mounted adjacent to the picker-stick slot, a bushing pivotally held on said plate and having a flange extending partially around its periphery, a check-blade 100 pivotally mounted on said bushing, a spring coiled around said bushing between said blade and said flange and having one end engaging one end of said flange, or the other according to whether the check is right or left hand, the other end of said spring extending back of 105 said blade, and an adjustable stop on said plate to limit the movement of said blade under the influence of said spring.

5. A picker-stick check for looms, comprising 110 a plate having an offset portion adapted to be mounted adjacent to the slot in the lay-beam, a bolt passing through a transverse slot in said offset portion, a bushing surrounding said bolt and adapted to be clamped between said offset portion and the nut of the bolt, a flange 115 extending around a portion of the periphery of said bushing, a check-blade pivotally mounted on said bushing, a spring surrounding said bushing adjacent to said blade, one end thereof engaging one end of said flange and the other end extending back of said blade, a bracket on the back of said blade carrying 120 a lug, a block slideable transversely on said offset portion and carrying a stop to coöperate with the lug on the blade to limit the movement of said blade under the influence of said 125 spring, and means to clamp said block to said offset portion.

6. A picker-stick check for looms, compris-

ing a plate having an offset portion adapted to be mounted adjacent to the picker-stick slot in the lay-beam, a bolt passing through a transverse slot in said offset portion, a bushing surrounding said bolt and adapted to be clamped between said offset portion and the nut of said bolt, said bushing having a reduced circular portion adjacent to the offset portion of said plate, a larger circular portion adjacent to said reduced portion, an angular portion adjacent to said larger portion and flanges on said larger portion adjacent to said angular portion, each of said flanges extending only partially around the periphery of said bushing and one of said flanges having recesses formed in its ends, a check-blade pivoted on said reduced portion, a spring coiled around said larger portion and having one end engaging one of said recesses and the other end extending back of said blade, a hook-shaped stop on the back of said blade and a coöperating adjustable stop on said plate to limit the movement of said blade under the influence of said spring.

25 7. A picker-stick check for looms, comprising a blade adapted to be pivotally mounted adjacent to the picker-stick slot in the lay-beam, the face of said blade being concaved so as to offer a gradually-increasing resistance to the picker-stick, a stop-bracket attached to the

back of said blade at approximately the longitudinal and vertical center thereof, a coöperating stop-lug mounted on the lay-beam, and a spring attached to the pivot of said blade and extending to a point adjacent to said stop-bracket, the attaching means of said spring being reversible according to which side of the picker-stick slot the blade is mounted.

35

8. A picker-stick check for looms, comprising a check-blade adapted to be pivotally mounted adjacent to the picker-stick slot in the lay-beam, the face of said blade being constructed to offer an increasing resistance to the picker-stick, coöperating stops on said blade and on the lay-beam to limit the movement of said blade toward the picker-stick slot, a spring reversibly attached to the pivot of said blade and extending back thereof to a point adjacent to said stops, the pivot of said blade and the stop on the lay-beam being adjustable toward and away from the picker-stick slot.

40

In testimony whereof I have signed my name to this specification in the presence of two subscribing witnesses.
